UNITED STATES PATENT OFFICE

FRITZ KENNEL, OF WEISSENFELS, O. S., GERMANY, ASSIGNOR TO THE FIRM OF
NOLLESCHE WERKE KOMM.-GES., OF WEISSENFELS, O. S., GERMANY

LASTING MACHINE

Application filed March 27, 1929, Serial No. 350,363, and in Germany April 5, 1928.

This invention relates to lasting machines and more particularly to the arrangement of means for forming slits in the upper material at the toe of the shoe to make the plaits lie smooth upon the insole.

The slitting means shown in the U. S. Patent No. 931,809 have proved very effective and advantageous so far as their operation is concerned. They move in a broken line to engage, penetrate and slit the upper. This operation gives satisfactory cuts and smooth plaits but the known arrangement has serious drawbacks inasmuch as the slitting means are arranged on a bracket accommodated between the working points of the lasting and slitting instrumentalities and the place occupied by the attendant. The attendant is therefore unable to observe the progress of the work.

The object of the present invention is to obviate these drawbacks and to arrange the slitting means of the kind described in the above patent behind the working points of the said instrumentalities so that these points may be easily inspected.

A further object is to improve the operation and to simplify the construction of the machine referred to.

To this end the two sliding carriers onto which the slitting bars are pivoted are accommodated in separate housings and these housings are arranged on either side of the pincers and of the nailing and wiping devices on the machine frame behind the working points of the slitting knives. Preferably these housings are arranged partly or wholly underneath the common wiper.

These and other features of the invention, including certain details of construction and arrangements of parts will be hereinafter described and pointed out in the claims.

The lasting machine herein shown is fully described in the U. S. Patent No. 584,744 to which reference may be made for details of construction.

In the accompanying drawings which illustrate a preferred embodiment of the invention, Fig. 1 is a side elevation of a part of the machine; Fig. 2 is a front elevation with the slitting bars broken away. Fig. 3 is

a horizontal cross-section on the line $x-y$ of Fig. 1; Fig. 4 is a rear elevation; Figs. 5 to 8 illustrate the different phases of operation of a slitting device; and Figs. 9, 9a and 10, 10a illustrate by way of comparison the path of the point of the slitting knife according to the invention and to the U. S. Patent 931,809 respectively; Fig. 11 is a section on the line $s-t$ of Fig. 8.

The knives 1 and 2 are pivoted at 11 to the slides 10 guided in housings 50. These slides are provided with racks 10'. These racks are engaged by the toothed segments 9 revolubly mounted upon the pivots 9'. To the same pivots are fastened the gears 8 which are in mesh with the racks 7. These racks have dogs 6 adapted to be engaged by the notches 5 of the bar 3. The bar 3 is attached to the slide 24 by means of the pivot 4. The slide 24 is connected by the parts 22, 21 and 20b to the lever 20a which is oscillated by the cam-disk 18 keyed to the shaft 17 journalled in the machine frame 23. By these means an endwise movement is imparted to the bar 3 which can also be swung laterally in a horizontal plane about the pivot 4 in order to bring the dog 6 of the left or the right rack bar 7 in engagement with one of the notches 5 of the bar 3.

As the bars 7 are connected by gears to the slides 10 their to and fro movement is transmitted to the knife 1 or 2 according to the left or right position of the bar 3. A pin 16 of the bar 3 projects into a slot of the member 15 which can be moved by the knee of the attendant to the left or to the right. To this end the member 15 forms a slide movable in the guide 15' and has a pin

14 engaging a slot 14' of the vertical slide 13 likewise movable in the guide 15'. This guide 13 is attached by means of the arm 35 to the vertical bar 34. The bar 34 engages by a roller 33 into an inclined groove 32 of the knee-lever 31. By swinging of the knee-lever 31 the knife 1 or 2 is brought at will into bearing with the said cam-disk 18.

By the same movement of the knee-lever the pincers 36 perform their plaiting movement as well known in the art. If no slitting is to be performed while the plaiting is going on the lever 20a is brought out of bearing with the said

cam-disk. This is obtained by connecting the levers 20a and 20b by spring pressed studs 25. The studs 25 can be disengaged from the lever 20a by means of the wedge shaped ends of the slide 26. The lever 20a then oscillates while the lever 20b remains at rest. The slide 26 is connected to the lever 27 which is kept in the uncoupled position by the spring 37. The lever 27 can be pulled out by hand where it becomes locked by the pawl 38.

Fig. 5 shows the left knife in its position of rest on the left side of the wiper 39. In the position illustrated in Fig. 6 the knife has partially completed its swinging movement toward the work and has just engaged the upper. While the slide 10 is moving from the position shown in Fig. 5 into the position shown in Fig. 6 the cam 30 at the end of the knife-lever 12 strikes against the block 28 which thus causes the knife to swing and to come before the wiper 39. While the slide 10 continues its forward movement the knife makes a drawing slit into the margin of the upper as seen in Fig. 7. The further forward movement of the slide 10 brings the cam 30 of the knife-lever 12 out of contact with the block 28 and is swung away from the shoe by the spring 29 so that the knife-holder 12 occupies the position shown in Fig. 8. The block 28 is a plunger pressed upwardly by a spring. Now the slide 10 returns to the rear and the cam-end 30 of the knife-lever 12 rides over the inclined upper surface of the block 28 which is thus pushed down against its supporting spring. At the end of its rearward movement the block 28 moves again upwardly and assumes its normal position as shown in Fig. 5. The whole path of the knife point is shown by dotted lines in Fig. 8.

Referring now to Figs. 9 and 9a the pivot 11 of the knife-lever 12 while approaching the shoe moves from the point *a* to the point *b* in a straight line. At the same time the lever 12 swings about the said pivot *a* along the circular line *a'*, *a''*. The latter combines with the path *a''*, *b'* which is equal to the line *a*, *b* to the resulting path *a'*, *b'* which is the real path of the engaging point of the knife. This resulting path is vertical or almost perpendicular to the slitting direction which is indicated in Fig. 9a by an arrow. Thus the engaging point of the knife does not appreciably change its position in the cutting direction while piercing the upper. Attention now being directed to Figs. 10 and 10a illustrating the mode of operation of the cutting device of the U. S. Patent 931,809 where like numerals indicate like parts as in the said patent it will be observed that the knife-carrier 58 moves along the line *a*, *b* in a reverse direction to the direction of slitting. At the same time this carrier swings about the pivot *a*. The corresponding paths of the engaging point of the knife 66 are *a''*, *b'* and *a'*, *a''* respectively. The resulting path is designated

by *n'*. This path is necessary for the known device to bring the knife to the upper. At the end of this resulting path the knife begins to move backwardly in the cutting direction. The knife-carrier 58 returns along the path *b*, *c* and continues to swing inwardly. The corresponding paths of the engaging point of the knife are *b''*, *c'* and *b'*, *b''* respectively. The resulting path is *n''*. The point of the knife engages therefore the upper at *b'* and moves along from *b'* to *c'* in order to pierce the leather. Thus the engaging point of the knife changes its position in the cutting direction before fully piercing the upper. After the piercing the knife moves in a straight line and slits the margin of the upper. In distinction to the new device which pierces the leather in the vicinity of the first engagement, that is in the point *b'* of Fig. 9a, the known device engages the upper at the point *b'* of Fig. 10a and pierces it fully at the point *c'*. The effect of this difference is that the plaits made with the lasting machine equipped with the new device begin at the point *b'* of Fig. 9a of the engagement of the slitting knife while in the machine equipped with the known device the plaits begin at the point *c'* at the end of the line *b'*, *c'*. This difference is due to the fact that according to the present invention the line *a'*, *a''* of this inward swinging is reversely directed to the cutting direction while with the known device the direction of the swinging path *a'*, *a''* is identical with the direction of the slitting movement. This is a very important advantage of the new arrangement while the other advantages residing in the unobstructed view of the attendant and in the simplicity of construction accrue from the arrangement of the slitting devices beneath the wiper nearer the machine-shaft.

While only the operation of the left knife is described it is needless to say that the right knife operates in an analogous way.

What I claim is;

1. In a lasting machine of the class described, lasting pincers in the front of the machine, two pivoted knife-levers, two slides carrying the knife-levers, a wiper, and two housings for the slides on either side of the wiper behind the pincers.

2. In a lasting machine of the class described, lasting pincers in the front of the machine, two pivoted knife-levers, two slides carrying the knife-levers, a wiper, two housings for the slides fastened to the machine-frame on either side of the wiper behind the pincers, and yielding blocks within the housings adapted to swing the knife levers inward and to be pushed out of the way by the returning knife-levers.

3. In a lasting machine of the class described, lasting pincers in the front of the machine, two pivoted knife-levers, two slides carrying the knife-levers, a wiper, two housings

ings for the slides fastened to the machine-frame on either side of the wiper behind the pincers, racks on the lower surfaces of the slides, gears underneath the housings meshing with the racks, and a bar reciprocated in a horizontal plane by the machine drive and adapted to be coupled with the gears moving either the right or the left slide.

4. In a lasting machine of the class described, lasting pinchers in the front of the machine, two pivoted knife-levers, two slides carrying the knife-levers, a wiper, and two housings for the slides on either side of and partly underneath the wiper behind the pincers.

5. In a lasting machine of the class described, lasting pinchers in the front of the machine, slitting knives supported behind the pincers, and means for moving said slitting knives along broken paths.

6. In a lasting machine of the class described, lasting pinchers in the front of the machine, slitting knives behind the pincers, and means for causing said knives to approach the work by a swinging movement while simultaneously moving in the slitting direction.

7. In a lasting machine of the class described, lasting pinchers in the front of the machine, slitting knives behind the pincers, and means for causing said knives to pierce the leather by moving in the slitting direction while simultaneously swinging toward the work.

35 In testimony whereof I affix my signature.
FRITZ KENNEL.
